INVENTOR.
Michel May,
BY

Geo. Kimmel. ATTORNEY.

UNITED STATES PATENT OFFICE.

MICHEL MAY, OF LOS ANGELES, CALIFORNIA.

HEAT RETAINING AND CONDUCTING ATTACHMENT FOR BURNER STOVES.

Application filed April 30, 1921. Serial No. 465,919.

To all whom it may concern:

Be it known that I, MICHEL MAY, a citizen of the United States, residing at Los Angeles, in the county of Los Angeles and 5 State of California, have invented certain new and useful Improvements in a Heat Retaining and Conducting Attachment for Burner Stoves, of which the following is a specification.

10 This invention relates to a heat retaining and conducting attachment for burner stoves, of that type provided with burners for utilizing gas, gasoline, oil, or vapor, as a fuel to generate heat for cooking or other 15 purposes, and has for its object to provide in a manner as hereinafter referred to, an attachment for seating on the stove over the burners and including means whereby the heat from one burner can be conducted 20 to one or a plurality of points to be utilized for heating more than one vessel, under such conditions providing for a saving in the consumption of fuel, and to furthermore provide the attachment with means whereby the 25 heat can be retained within one portion thereof so as to be used solely in connection with the heating of a single vessel.

Further objects of the invention are to 30 provide an attachment for the purpose referred to and in a manner as hereinafter set forth, and which is comparatively simple in its construction and arrangement, strong, durable, compact, efficient and convenient in its use, readily set up, and comparatively inexpensive to manufacture.

With the foregoing and other objects in view, the invention consists in the novel construction, combination and arrangement of parts as hereinafter more specifically 40 described, and illustrated in the accompanying drawings, wherein is shown an embodiment of the invention, but it is to be understood that changes, variations and modifications can be resorted to which fall within the 45 scope of the claims hereunto appended.

In the drawings, wherein like reference characters denote corresponding parts throughout the several views:—

Figure 1 is a top plan view, of an attachment in accordance with this invention, with the same extended.

Fig. 2 is a view looking toward the extensible end of the attachment.

Fig. 3 is a side elevation.

Referring to the drawings in detail, a

heat retaining and conducting attachment in accordance with this invention, is formed of two sections, one of which is termed a body portion, and the other section an extensible slide. The body portion is formed of a shallow rectangular receptacle including a top wall 7, a pair of imperforate side walls 7', an imperforate end wall 5', an open end 5'', and a bottom 6' of less width and of less length than the width and length of the top 7, and which is connected with the side walls 7', end wall 5' and top 7. The side wall 7', and end wall 5' are connected to the lower face of the top 7 inwardly with respect to the side and end edges of said top 70 whereby the latter will project laterally from the said side and end walls.

The extensible slide is shiftably mounted in the body portion and extends through the open end 5'' thereof, and is hollow, as well as shallow, and is formed with an open inner end, a top 15, a bottom 16, which is imperforate, an imperforate outer end wall 1', and a pair of imperforate side walls 1.

The slide is arranged to slide snugly yet 80 freely into one end of the body portion so that, when desired, the opening in the side may be moved into coincidence with an opening in the top 7 of the body so as to register with the same and this opening may have the 85 usual grating used in connection with gas or oil stoves.

The body portion has the top 7 thereof, at a point between its center and the closed end of the body portion, provided with an opening, and the bottom 6' of the body portion is also provided with an opening, the latter registering with the said opening in the top 7. Depending from the bottom 6' of the body portion, is a collar.

Arranged within the body portion and interposed between the opening in the top 7, is a damper capable of retaining heat within the body portion at that part provided with the registering openings, or permitting of 100 the heat to pass into that part of the body portion provided with the other opening and also into the extensible slide.

Vessels can be mounted on the openings in the top 7 and on the opening in the slide, that is to say supported by the top 7 over the two openings in the top and by the slide over the opening in the slide.

The damper is under the control of a 110 handle shown in Fig. 3.

The collar is placed around the burner which coincides with the rear opening to prevent cool air from passing into body portion while the burner is active.

5 When anything to be heated is placed over the rear opening, it will be so placed that the heat cannot pass out around it and thereby the heat is shut in and forced to pass along the interior of the body portion to the other 10 opening thus conducting the heat and using it twice.

The body portion of the attachment may be of any form desired and is made of any weight of material which will withstand heat suitable for the kind of use desired.

In Fig. 1, there is indicated a handle by means of which the slide may be moved into and out of the body portion.

The bottom 16 of the slide has no opening through it.

The general form of the heater is that of a simple heat tight flat box with a flange all around the top edge but not on the bottom and having two or more openings through the top or one side and one opening only at the bottom or other side.

The material employed in making the instrument is metal, which can withstand heat and of a thickness and weight to suit the purposes for which it is used.

The size of the instrument is in accordance with the purpose for which it is to be used, whether for heavy or for light work.

What is claimed is:—

35 1. An attachment for the purpose set forth comprising a shallow rectangular receptacle including a pair of side walls, a bottom, a top, a closed end wall and an open end, said top provided at a point between its transverse center and each end with an opening, said bottom provided between its transverse center and the closed end of the receptacle with an opening arranged below one of the openings in the top, and a shallow rectangular slide including a pair of side walls, a bottom, a top, a closed outer end wall and an open inner end, said slide mounted in the open inner end of said receptacle and permanently communicating therewith, said slide of a length not more than half the length of said receptacle whereby said receptacle is opened for the inlet of combustion products when the slide is completely within the receptacle and said slide having its top provided with an opening capable of registering with one of the openings in the top of the receptacle when the slide is shifted inwardly, the opening in the top of said slide providing means for heating a vessel when the slide is withdrawn from the receptacle to position the opening of the slide exteriorly of the receptacle, the openings in the top of said receptacle providing means for heating a vessel mounted thereover, and a collar connected with and

depending from the bottom of the receptacle and communicating with that opening in the bottom of the receptacle arranged between the transverse center and the closed end of the receptacle.

2. An attachment for the purpose set

forth comprising a shallow rectangular receptacle including a pair of side walls, a bottom, a top, a closed end wall and an open

end, said top provided at a point between its transverse center and each end with an opening, said bottom provided between its trans- 75

verse center and the closed end of the receptacle with an opening arranged below one of the openings in the top, and a shallow rec- 80

tangular slide including a pair of side walls, a bottom, a top, a closed outer end wall and an open inner end, said slide mounted in

the open inner end of said receptacle and permanently communicating therewith, said slide of a length not more than half the

length of said receptacle whereby said receptacle is opened for the inlet of combustion products when the slide is completely

within the receptacle and said slide having its top provided with an opening capable of registering with one of the openings in the

registering with the top of the receptacle when the slide is shifted inwardly, the opening in the top of said slide providing means for heating a vessel 93

and providing means for sealing a vessel when the slide is withdrawn from the receptacle to position the opening of the slide exteriorly of the receptacle, the openings in

exterior of the receptacle, the flanges in the top of said receptacle providing means for heating a vessel mounted thereover, a collar connected with and depending from

corolla connected with and depending from the bottom of the receptacle and communicating with that opening in the bottom of the receptacle arranged between the trans-

the receptacle arranged between the transverse center and the closed end of the receptacle, and a transversely extending damper positioned within said receptacle.

3. An attachment for the purpose set forth comprising a shallow rectangular receptacle centrally positioned within said receptacle centrally thereof.

forth comprising a shallow rectangular receptacle including a pair of side walls, a bottom, a top, a closed end wall and an open end said top provided at a point between its

end, said top provided at a point between its transverse center and each end with an opening, said bottom provided between its transverse center and the closed end of the

transverse center and the closed end of the receptacle with an opening arranged below one of the openings in the top, a shallow

rectangular slide including a pair of side walls, a bottom, a top, a closed outer end wall and an open inner end, said slide

mounted in the open inner end of said receptacle and permanently communicating therewith, said slide of a length not more than half the width of the

than half the length of said receptacle whereby said receptacle is opened for the inlet of combustion products when the slide is

completely within the receptacle and said slide having its top provided with an opening capable of registering with one of the

openings in the top of the receptacle when the slide is shifted inwardly, the opening in the top of said slide providing means for heating a vessel when the slide is withdrawn 5 from the receptacle to position the opening of the slide exteriorly of the receptacle, the openings in the top of said receptacle providing means for heating a vessel mounted thereover, a collar connected with and 10 pending from the bottom of the receptacle and communicating with that opening in the bottom of the receptacle arranged between the transverse center and the closed end of the receptacle, a transversely extending damper positioned within said receptacle 15 centrally thereof, and said receptacle at its top provided with a laterally extending continuous flange.

In testimony whereof, I have hereunto set my hand in the presence of two subscribing 20 witnesses.

MICHEL MAY.
